UNITED STATES PATENT OFFICE.

HANS K. LORENTZEN, OF NEW YORK, N. Y.

VENDING MACHINE.

Application filed January 8, 1920, Serial No. 350,170. Renewed August 26, 1927.

My present invention relates to vending machines of the type such as are ordinarily applied to the backs of theatre chairs and the like for vending small packages of candy, 5 chocolate and the like.

The objects of the invention are to provide a machine of this character which will be positive and reliable in action, relatively simple and inexpensive, comparatively small and 10 compact, durable and capable of withstanding hard usage and which, furthermore, will be properly protected against the use of spurious coins and safeguarded against improper action or use thereof.

15 In this latter connection, a special object of the invention is to safeguard both the owner of the machine and the public by preventing refilling or removal of the machine, except by one authorized for such purposes.

20 These and other objects I have accomplished by a novel construction, combination and relation of parts, a commercial example of which is illustrated in the accompanying drawings wherein:

25 Figure 1 is a perspective front view of the machine.

Figure 2 is a front view of the machine with parts removed to expose the key actuated coin releasing mechanism.

30 Figure 3 is a detail perspective view of the supporting bracket.

Figure 4 is a face view of the supporting plate carrying the coin actuated lock releasing mechanism.

35 Figure 5 is a rear view of the same, with the levers for shifting the locking slides broken away and shown in dotted lines.

Figure 6 is a vertical sectional view of such parts as taken on substantially the plane 40 of line 6—6 of Figure 4 and showing one of the detecting levers first in its normal position and secondly in the position it occupies when engaged by a coin of proper thickness.

Figure 7 is a vertical sectional view taken 45 on substantially the plane of line 7—7 of Figure 5 and showing positions of the second coin gaging lever.

Figures 8 and 9 are detached edge and face views of these two levers.

50 Figure 10 is a broken detail view of the key actuated coin releasing slide and the bracket engaging locking slide operated therefrom.

55 Figure 11 is a front view with different parts of the walls of the casing broken away to show the article delivery mechanism,

which latter is indicated in the retracted position.

Figure 12 is a fragmentary view illustrating the delivery slides in the projected position.

Figure 13 is a vertical sectional view as taken on substantially the plane of line 13—13 of Figure 11.

Figure 14 is a horizontal sectional view 65 taken on substantially the plane of line 14—14 of Figure 12.

The machine of the present disclosure is designed for vending relatively long and flat 70 oblong packages of candy or the like and is 75 constructed to hold two of such packages at a time. These packages are supported on the slides 20 (Figure 11), guided at opposite sides of the vertical partition wall 21 and are confined in sliding engagement with said 80 wall by means of the angularly turned lugs 22 at their upper ends working in the slots 23 in such partition. These slots are shown in Figure 13 as open at their upper ends and as closed by a clip 24 which forms a stop limiting the outward or projecting movements of the slides.

In the construction illustrated the packages are actually supported on shelves 25 adjustably secured to the slides by screws 26 passing through slots 27 in the angular base ends of such shelves into selected screw seats 28 in the slides. This construction provides for the adjustment of the machine to different 90 lengths of packages.

The delivery slides are projected by springs 29 engaging the angularly out-turned lower ends 30 of the slides. These springs are furthermore utilized as a means for rocking the stop posts 31 on their pivots 32 toward 95 the right in Figures 11 and 12, said springs being indicated as having their lower ends engaged with the angularly outstanding feet 33 at the lower ends of such posts. This tipping of the posts causes them to operate as 100 spring pressed pawls for holding the delivery slides in their projected position until the machine is recharged by an attendant equipped with the proper key. For this purpose the lower ends of the delivery slides are 105 formed with openings 34 to receive the posts when the machine has been unlocked by an attendant and is being recharged with fresh packages. This condition is illustrated in Figure 12. When the machine has been 110 charged and again locked, the locking posts will stand in the position indicated in Fig-

ure 11, where a projecting foot portion 35 at one edge of each post will stand substantially in line with the adjacent edge of the opening 34 in the delivery slide. As the slide is projected, the post is rocked to the left, in Figure 11, by the engagement of such edge of opening 34 with the foot portion 35, and as the delivery slide moves outward, the post is snapped to the right so as to bring the foot portion 35 into holding engagement beneath the lower end of the delivery slide. To release the delivery slides so that they can be retracted, the locking posts are moved to the left, as indicated in Figure 12, by shifting the slide 36 on which they are mounted so as to bring them again fully into register with the openings 34 in the bottoms of the delivery slides.

The box or casing 37 of the machine is closed at the top by the doors 38 pivoted at 39 and each constituting a closure over one of the delivery slides. These doors are secured closed by coin or check controlled lock mechanisms now to be described and which are arranged to permit independent operation of either of the delivery mechanisms.

40, 40 in Figure 1 designate two thumb-knobs or finger-holds rotatably journaled in a cover plate 41 secured over the front of the casing in position to cover the interior parts of the locking and tripping mechanism. These thumb-turns are freely rotatable in the support 41 and are normally entirely disconnected and free of other parts so that they 35 may be turned at will without injury to any of the mechanisms. At the inside of the cover plate 41 the thumb-turns are formed with a partially circular coin pocket 42 open at the rear and also at the edge thereof so as to receive the coin or check 43 edgewise thereinto. These coins or checks are inserted through openings 44 provided therefor in the cover plate and the parts are so designed that the coins when caught in the pockets provided therefor, will constitute connecting links between the finger operated coin holders and levers for retracting the lock mechanism. These levers are designated 45 and are shown in Figure 4 as pivoted at 46 intermediate their ends and as provided at their lower ends with cam surfaces 47 projecting into the paths of the coins on the rotatable coin holders so as to be actuated thereby.

At their upper ends these levers engage with the lugs 48 of the locking slides 49 which are constructed with lugs or hooks 50 to engage with the lugs or hooks 51 carried by the covers 38.

For the sake of compactness and greater 60 simplicity I have shown in the present embodiment the retracting levers and associated lock mechanism all mounted on a single supporting plate 52 which is secured on the front of the casing directly beneath the cover plate 41. The retracting levers are mounted on

the front face of this supporting plate in position to be engaged by the coins in the coin pockets and the cover locking slides 49 are indicated as slidingly mounted on the back of said supporting plate on the pins 53, the lugs 70 48 on said locking slides projecting through slots 54 to the front of the supporting plate in position to be engaged by the upper ends of levers 45.

As the coin holders are turned from the 75 position indicated at the right in Figure 4 to the position shown at the left in that view, the coins are held in the pockets provided therefor by means of a partly circular guard flange 55. This flange also operates as a stop 80 to prevent passage of coins of greater diameter than the size predetermined upon.

Additional safeguards against the use of spurious coin are provided in the form of detectors having gage fingers 56 and 57 projecting, the first, into the rim portion of the coin path and the second, into the central portion of the coin path. The detector finger 56 is in the form of an inclined cam or gage finger curved longitudinally and projecting through a slot provided therefor in the supporting plate 52 from a lever 58 pivoted at 59 on the back of the supporting plate. The finger 57 is in the form of a pin or stud projecting through an opening in the supporting plate from a lever 60 pivoted on the back of the plate at 61 and having a yielding connection with the free end of the lever 58 by means of the spring 62.

The lever 58 also carries at its free end an 100 angularly turned lug 63 projecting through an opening in the supporting plate into position behind the lower end of the retracting lever 45. Similarly, the gaging lever 60 carries at its free end an angularly turned lug 64 projecting through an opening in the supporting plate into position in front of the upper end of the retracting lever 45. Each of the retracting levers is normally pressed back into position where these stops 63 and 64 will stand in operative engagement therewith by means of the springs 65. The gaging levers 60 are pressed out at their free ends by the springs 66.

From the description thus far it will be 115 apparent that the machine, when charged, is locked closed by the locking slides 49 which secure the covers over the two delivery slides. When a coin of the proper size is inserted through one of the slots 44 and into the pocket in one of the thumb-turns, a partial rotation of such thumb-turn will cause the coin in its rotation to depress the detector cam 56. This will rock the lever 58 carrying such cam and thereby cause such lever to retract the stop lug 63 from the path of the lock retracting lever 45 that is, if the inserted coin is of the proper thickness and therefore capable of shifting lever 58 to the necessary extent. The movement thus imparted to 125 130

lever 58 through the spring connection 62 has a tendency to rock the second detector lever 60 so as to cause the locking lug 64 of such second lever to stand in the path of movement of lock retracting lever 45. This tendency is overcome, however, by the engagement of the feeler finger 57 of the second detector lever with the central portion of the coin, provided again that the coin is of proper thickness. If the coin is too thin at this point, or if a ring were used in place of a coin, there would be nothing to stop the pin 57 and hence the lug 64 would prevent lock-retracting movement of lever 45.

15 It will be seen, therefore, that if the inserted coin or check is of the proper diameter and thickness, the mechanism can be operated to release the cover and permit the delivery spring to operate the delivery slide. 20 When this is done, the spring pawl 31 (Figures 11 and 12) snaps under the delivery slide and holds the same in projected position. Also, the cover which has been opened is preferably held open as by means of a 25 spring 67, so as to indicate at a glance to an attendant the necessity for refilling.

The coins for operating the releasing mechanism drop into a chamber 68 formed in the front of the casing beneath the cover plate 30 41. The coins can be released from this chamber by an attendant having a proper key. The mechanism which makes this possible is illustrated in Figures 2 and 10 and comprises generally a coin chute in the bottom of the compartment 68 having a fixed wall 69 and a relatively movable wall 70, the latter serving, when extended, to close the chute against the escape of coins and adapted, when retracted by means of a key such as that indicated at 71, to open the chute sufficiently 40 to permit the coins to fall out into the hand of the attendant. This movable wall 70 of the coin chute is shown as carried by a slide 72 locked normally by suitable tumblers 73 and 45 preferably constructed so as to be retracted by the simple insertion of the proper key.

The insertion of the key 71 in the construction disclosed also serves to shift the slide 36 (Figures 11 and 12) so as to unlock the delivery slides. This is made possible by means of a pin 74 projecting rearwardly from the key slide 72 and engaging the forked upper end of a lever 75 which is pivoted at 76 and which connects at its lower end at 77 with the slide 36. Figure 12 illustrates the condition where the key has been inserted and the lever 75 has been rocked to free the stops 31 from the delivery slides so as to permit said slides being charged with fresh articles.

When the fresh packages are thus placed on the delivery slides and the slides are pressed back into the casing, the covers can again be closed and locked. This is because of the fact that the slides, as they are retracted,

operate to shift the locking slides 49 into locking engagement with the covers through the medium of levers 78 pivoted at 79 and engaging behind the locking slides 49 at their upper ends (Figure 5) and terminating in 70 spring arms 80 at their lower ends engaged by the outstanding pins 81 on the delivery slides.

For supporting the machine on the back of a theatre chair or the like I have provided a bracket 82 suitably secured to the support and provided at its upper end with a supporting edge 83 for engagement by the hooks or lugs 84 on the back of the casing and at its lower end with a rearwardly projecting hook 85 arranged to extend into the lower end of the casing (Figure 14) into position to be caught by a hook or lug 86 on the slide 36. Normally, the parts stand in the position shown in Figure 14 with the locking 80 slide engaged with the bracket and the machine thereby securely locked on its supporting bracket. When, however, the key is inserted in the lock, the slide 36 is shifted over to the position shown in Figure 12 and this serves to clear the shoulder 86 from the shoulder 85 thereby freeing the lower end of the machine from the bracket and permitting the machine to be bodily lifted off the bracket.

This is important where it is necessary to 95 repair the machine, or in some cases, where it is desirable to substitute one machine for another.

The detector cam 56 is of particular utility in detecting and preventing operation of the machine by discs of cardboard, for instance, or other relatively soft material, said cam in such a case compressing the cardboard rather than being moved thereby and thus operating the same way as in the case of a 100 check or coin which is too thin. The force of this cam also serves to throw the spurious check of cardboard or the like backward out of the pocket in the thumb-knob, sufficient space being left back of the coin holder 40 to 105 admit of this operation. The detector levers operate sequentially, the first one being actuated by the cam 56 and then, the first requirements as to the size of the operating check having been fulfilled, the second detector 110 57 operates to determine whether other requirements, as to thickness at the center of the check, are properly met. The one is thus, in a sense, independent of the other, but both must be operated to the proper degree and in 115 the order mentioned before the machine will operate.

The detector 57 might in fact be termed a "washer" detector because of the fact that it detects washers or rings and a special point of this detector already brought out, but in a somewhat different way, is that it is actuated through the cam detector by the washer which is being calipered or measured.

The coin is, as illustrated, preferably seated in the coin holder, well inward past the center of the coin holder as clearly shown in Figure 4, so as to be firmly held therein and so as not to protrude too far therefrom.

It will be apparent from the foregoing that the device of this invention is extremely compact for the results which it accomplishes and further that it is simple, durable and practical in every respect. While the form shown is found to possess many advantages and to be desirable from a manufacturing point of view, I would have it understood that changes and modifications may be made without departure from the true spirit and scope of the invention. I would also have it understood that the terms employed herein are used in a descriptive rather than in a limiting sense, except, however, for such limitations as may be imposed by the prior art.

What I claim is:

1. In combination, a vending machine provided with a lock, a pivoted trip mechanism for releasing said lock, a pivoted stop lever having a lug normally in engagement with the trip mechanism and a rotatable operating member disconnected from said trip mechanism and normally free to turn, said member being provided with a pocket to support a check of predetermined size in position to swing said lever on its pivot to initially withdraw the lug from engagement with the trip mechanism and then form a driving connection between said freely turning member and the trip mechanism.

2. In combination, a vending machine provided with a lock, a pivoted trip mechanism for releasing said lock, a pivoted lever mechanism having portions engageable with said trip mechanism for normally locking the trip mechanism and a rotatable coin holder free of said trip mechanism provided with an external thumb-piece and having a pocket to support a coin of predetermined size in position to initially operate the trip locking mechanism and subsequently form an operating connection between the coin holder and trip mechanism.

3. In a vending machine, locking mechanism, check controlled unlocking mechanism for said locking mechanism including a trip releasing lever pivoted intermediate its ends and engageable with said locking mechanism, locking devices for said trip engageable with opposite end portions of said lever and a coin holder for supporting a coin to operate the trip and to release the same from locking position.

4. In a vending machine, lock mechanism, a pivoted trip lever for releasing the same, a movable coin holder for carrying a coin in position to engage and operate said lever, locking devices for said lever and detector mechanism for releasing said locking devices

and disposed to engage the coin carried by said coin holder.

5. In a vending machine, lock mechanism, a movable trip for releasing the same, a movable coin holder for carrying a coin into position to operate said trip, locking devices for said trip and movable gages positioned to engage the rim and central portions of a coin on the coin holder and connected to release the locking devices. 75

6. In a vending machine, lock mechanism and means for releasing the same comprising a rotatable coin holder having a coin pocket open at the rear, gages disposed adjacent said open coin pocket, a trip lever having a portion disposed in the plane of the coin holder to be thereby engaged by a coin in said pocket and locking devices for said lever controlled by the gages aforesaid. 75

7. In a vending machine, lock mechanism and means for releasing the same comprising a rotatable coin holder having a coin pocket open at the edge and arranged to carry a coin of predetermined size with its rim projecting from said pocket, a guard flange around the open side of the coin pocket, trip mechanism having a portion disposed to be operated by the projecting rim of a coin of the predetermined size and pivoted levers for locking said trip mechanism, said levers having coin detecting means disposed within the guard flange to be engaged by the coin within the coin pocket. 90

8. In a vending machine, a cover, a lock therefor, a coin actuated lever for retracting said lock, coin gaging devices for controlling the operation of said lever, and means for supporting a coin to engage the gaging devices and to operate the lever. 100

9. A vending machine provided with a lock, a lever for retracting said lock, a movable coin holder for carrying a coin into position to actuate said lever, locking devices for engaging said lever and trips for said locking devices having gaging elements disposed in position to be engaged by the coin on the coin holder for releasing said locking devices. 110

10. In a vending machine, the combination of an article delivery slide and a cover over said slide, a lock for said cover, a lever for releasing said lock, a movable coin holder for supporting a coin in position to actuate said lever, independently operating locking devices for engaging said lever at different points and trips for said locking devices having coin gaging portions extending into different parts of the path of movement of the coin on the coin holder. 115

11. In a vending machine, an article delivery slide, a cover over said slide, a lock for said cover, means for releasing the lock comprising a coin actuated member and a plurality of levers provided with gage fingers for engagement with the coin and with locking 125 130

lugs for engagement with said member, and means for supporting a coin in position to engage the gage fingers and to actuate the releasing means.

5 12. In a vending machine, an article delivery slide, a cover over said slide, a lock for said cover, means for releasing the lock comprising a coin actuated member and a plurality of levers provided with gage fingers for engagement with the coin and with locking lugs for engagement with said member, said levers being interconnected and operative to release said member only when the coins engaged by the gage fingers thereof are of predetermined dimensions, and means for supporting a coin in position to engage the gaging fingers and to actuate the releasing means.

10 13. In a vending machine, an article delivery slide, a cover over said slide, a lock for said cover, a supporting plate, a coin actuated trip for said lock mounted on one face of said plate and locking devices for said trip mounted on the opposite face of the plate and provided with portions projecting through the plate for engagement with the trip and with the coin for actuating the same, and means for supporting a coin in position to engage the projecting portions and to actuate the trip.

15 14. In a vending machine, an article delivery slide, a cover over said slide, a lock for said cover, a coin actuated trip for said lock, locking devices for said trip having actuating portions projecting into the path of the coin movement and a yielding connection between said locking devices, and means for supporting a coin in position to engage the projecting portions and to actuate the trip.

20 15. In a vending machine, an article delivery slide, a cover over said slide, a lock for said cover, and coin actuated mechanism for releasing the lock and including lock operating means and yieldingly interconnected coin gaging devices controlling the operation of the same, and means for supporting a coin in position to engage the gaging devices and to actuate the trip.

25 16. In a vending machine, an article delivery slide, a cover over said slide, a lock for said cover, and coin actuated mechanism for releasing the lock including a coin actuated member and coin gaging devices for locking said member, and means for supporting a coin in position to engage the gaging devices and to actuate the trip.

30 17. In a vending machine, an article de-

livery slide, a cover over said slide, a slide for locking said cover, a lever actuated by the article delivery slide for shifting the locking slide to its securing position and coin actuated mechanism for releasing the locking slide including a lever for shifting said locking slide and coin gaging devices controlling operation of said lever.

35 18. In a vending machine, article delivery slides, covers over said slides, locking members for said covers, levers actuated by the slides for shifting the locking members to their cover securing positions and coin actuated mechanism for releasing the locking members including levers for shifting said locking members and coin gaging devices controlling operation of said levers.

40 19. In a vending machine, the combination with check actuated means and a plurality of pivotally mounted locking devices therefor, of a detector positioned in the path of the check and arranged to be displaced thereby, connections from said detector to one of the locking devices and a second detector arranged to engage the check after its engagement with the first detector and connected to control a second locking device and means to support a check in position to engage the check actuated means.

45 20. In a vending machine, coin actuated mechanism, pivotally mounted locking devices therefor, a washer detector controlling one of said locking devices and a second detector device controlling another of the locking devices positioned to be engaged by the inserted coin and arranged when actuated by said check to operate the washer detector and means to support a coin in position to engage the coin actuated mechanism.

50 21. In a vending machine, an article delivery slide, a cover over said slide, a lock for said cover, and means for releasing the lock comprising a coin actuated member and a plurality of levers in the path of the coin and provided with gage fingers for engagement with said coin and with locking lugs for engagement with said member.

55 22. In a vending machine, an article delivery slide, a cover, a lock for said cover, and coin actuated mechanism for releasing the lock and including lock operating means and yieldingly interconnecting coin engagement devices arranged in the path of the coin and controlling the operation of said lock operating means.

In testimony whereof I affix my signature.

HANS K. LORENTZEN.
